(57) **CLAIM**

The ornamental design for a food cradle, as shown and described.

DESCRIPTION

FIG. 1 is a front perspective view of a food cradle showing our new design;

FIG. 2 is a rear perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof;

FIG. 8 is a bottom view thereof;

FIG. 9 is a cross-sectional view taken along line 9-9 shown in FIG. 7;

FIG. 10 is a front perspective view of another embodiment of a food cradle;

FIG. 11 is a rear perspective view of the food cradle of FIG. 10;

FIG. 12 is a front view of the food cradle of FIG. 10;

FIG. 13 is a rear view of the food cradle of FIG. 10;

FIG. 14 is a right-side view of the food cradle of FIG. 10;

FIG. 15 is a left-side view of the food cradle of FIG. 10;

FIG. 16 is a top view of the food cradle of FIG. 10;

FIG. 17 is a bottom view of the food cradle of FIG. 10;

FIG. 18 is a cross-sectional view of the food cradle of FIG. 10 taken along line 18-18 shown in FIG. 16;

FIG. 19 is a front perspective view of another embodiment of a food cradle;

FIG. 20 is a rear perspective view of the food cradle of FIG. 19;

FIG. 21 is a front view of the food cradle of FIG. 19;

FIG. 22 is a rear view of the food cradle of FIG. 19;

FIG. 23 is a right-side view of the food cradle of FIG. 19;

FIG. 24 is a left-side view of the food cradle of FIG. 19;

FIG. 25 is a top view of the food cradle of FIG. 19;

FIG. 26 is a bottom view of the food cradle of FIG. 19;

FIG. 27 is a cross-sectional view of the food cradle of FIG. 25 taken along line 27-27 shown in FIG. 16;

(Continued)

FIG. 28 is a front perspective view of another embodiment of a food cradle;
 FIG. 29 is a rear perspective view of the food cradle of FIG. 28;
 FIG. 30 is a front view of the food cradle of FIG. 28;
 FIG. 31 is a rear view of the food cradle of FIG. 28;
 FIG. 32 is a right-side view of the food cradle of FIG. 28;
 FIG. 33 is a left-side view of the food cradle of FIG. 28;
 FIG. 34 is a top view of the food cradle of FIG. 28;
 FIG. 35 is a bottom view of the food cradle of FIG. 28; and,
 FIG. 36 is a cross-sectional view of the food cradle of FIG. 34 taken along line 36-36 shown in FIG. 16.
 The broken lines show portions of the food cradle which form no part of the claimed design.
